DESIGN FOR A GOLF CLUB HEAD

Gerald K. Geerlings, New Canaan, Conn., assignor to A. G. Spalding & Bros. Inc., New York, N. Y., a corporation of Delaware

Application April 27, 1939, Serial No. 84,594

Term of patent 14 years

To all whom it may concern:

Be it known that I, Gerald K. Geerlings, a citizen of the United States, residing at New Canaan, in the county of Fairfield and State of Connecticut, have invented a new, original, and ornamental Design for a Golf Club Head, of which the following is a specification, reference being had to the accompanying drawing, forming a part thereof, and in which:

The design is characterized by the grooved ornamentation as shown on the striking face of the golf club head.

I claim:

The ornamental design for a golf club head, substantially as shown and described.

GERALD K. GEERLINGS.
